SURFACE TREATMENT OF SHEET MATERIALS

Eugene P. Walker, William Earl Wray, and Julius B. Walker, Reidsville, N. C., assignors to The American Tobacco Company, New York, N. Y., a corporation of New Jersey

Application December 5, 1931. Serial No. 579,334

17 Claims. (Cl. 51—139)

The present invention relates to apparatus for, and processes of, surface treatment, and to the resulting surface-treated products, and it has a particular field of application in the surface treatment of continuous sheets or webs of materials, such as wrapping tissues, papers, films, and the like, which are being passed into a machine where they are to be further treated and/or utilized.

10 Although not restricted thereto the invention will be described in its application to the pre-treatment of a continuous sheet or web of material having a non-cohesive surfacing, such as moisture-proof transparent materials formed from cellulosic derivatives, for example, of the type known as "Cellophane", especially where the material after treatment is passed meditately or immediately into a wrapping machine, as for example, automatic machinery for continuously 15 wrapping cigarette packages and other tobacco 20 preparations.

It is frequently desirable to apply labels, stickers, tabs and/or stamps to the exterior of packages wrapped with such moisture-proof transparent materials having anti-adhesive surfacings, such surfacings being usually applied for the purpose of lending increased moisture resistance. It is most difficult and commercially impracticable to attach such stamps, labels or stickers directly 30 to such surfaces in view of the fact that the usual surfacings have no particular affinity for, or adhesive qualities in respect to, the various mucilages, glues, gums and other adhesive materials commercially utilized.

35 It is therefore an object of the present invention to treat the surface of such wrapping materials so that the wrapping tissue and/or the wrapped articles will readily receive and substantially permanently retain stamps, labels, stickers and/or tabs upon attachment thereto by the usual commercial adhesives.

In accomplishing this object it has been found desirable to abrade, scratch, roughen and/or remove portions of the anti-adhesive surface coating of such moisture-proof transparent wrapping materials. Labels, stickers and stamps, upon adhesive attachment to such treated portions of the surface of the wrapper or the wrapped package will be substantially permanently retained. In view of the fact that most of these wrapping materials are utilized because of their transparency and moisture-proof qualities, it is preferable to abrade or remove the surface over as small an area as possible since such surface treatment to a large degree destroys the transparency

and/or the moisture-proof qualities. In addition the surface treatment to remove or abrade the coating should be effected in such a manner as to weaken the strength of the wrapper as little as possible.

Another object is therefore to provide an apparatus and process for treating wrapping tissues and similar materials of the character described, which will remove, abrade or otherwise affect predetermined surface areas sufficiently to receive 60 gummed or adhesively attached stamps, labels, and so forth, without substantial injury to the wrapping materials, as by decreasing their transparency and/or moisture resistant qualities, and in such a manner that the strength of the wrapping material will be substantially unimpaired.

Ordinarily in commercial automatic wrapping machinery the wrapping materials are removed in the form of a continuous sheet or web from rolls and are continuously or intermittently fed 65 to the wrapping machine, the sheet being cut into suitable sized sections, which are then wrapped about the packages, all of these operations being timed so that they will be performed at predetermined intervals and in a desired sequence.

Another object of the present invention therefore is to provide an apparatus and process for automatically treating spaced portions of the surface of a continuous sheet of wrapping material being fed to a wrapping machine, said apparatus 70 being of such construction as to be operated incidentally to feeding of the wrapping material to the wrapping machine, and to be actuated directly or indirectly from the mechanism of said wrapping machine.

Still another object is to provide an apparatus and process for treating the surface of continuous sheets of wrapping tissues, which apparatus is so arranged and constructed that the surface treating element may be applied at one stage of the 75 operation, and then withdrawn at another stage of operation, all automatically and incidentally to operation of the machine utilizing the wrapping tissue.

Other objects are in part obvious and will be in 80 part pointed out during the course of the following description.

In one embodiment of the invention the surface treating mechanism or arrangement is supported upon the frame of a wrapping machine, 105 which may be of usual construction, and is preferably of the type commercially employed in wrapping cigarette packages with a transparent moisture-proof wrapping material. The continuous sheet of said material, upon being unrolled, 110

is caused to pass through the apparatus of the present invention before it is passed into the wrapping machine, or into the other processing machine. Customarily the continuous strip of 5 wrapping material is fed intermittently to the wrapping machine, and the mechanism of the present invention is most desirably arranged so that the surface of the wrapping material will only be processed or treated during intervals between the forward movement thereof.

In this embodiment the web or sheet of wrapping material is passed between two faces, a fixed backing face usually of a soft, pliable compressible material such as felt, and a rough abrading 15 face, preferably consisting of a belt or other applicator for carrying emery or another abrasive material. The belt may pass over a head, which is pressed against said backing face. During the contact the abrasive face may be readily reciprocated over the area of the surface of the wrapping tissue to be treated. This abrasion contact preferably only takes place during the period when the sheet of material is stationary, and is discontinued by withdrawal of the abrasive face and 20 its supporting head upon further advancement of said sheet.

During operation, the abrasive carrier is moved so that the abrasive surface will be gradually replaced and at the same time that portion of the 25 surface, which has already been contacted with the wrapping material and has been removed from the contacting head, is cleansed, as by a rotary brush. This cleansing operation will remove the dust and other abraded particles from carrier 30 thereby preparing it for further contact with the wrapping material.

The abrasive carrier may be automatically applied to, and withdrawn from, the surface of the 35 wrapping strip by a reciprocatory driving means actuated from the mechanism of the wrapping machine, while the reciprocation and cleansing of the abrasive carrier are most desirably effected from an independent power-source forming part 40 of the surface-treating mechanism of the present invention. The connection between the reciprocating driving means and the abrasive carrier is preferably resilient and adjustable, so that the contacting pressure between the abrasive carrier and wrapping tissue may be suitably regulated.

The independent power for the abrasive carrier reciprocating arrangement may conveniently take the form of an electric motor, which may 45 actuate a shaft, carrying the rotary brush and an eccentric arrangement, through a belt drive. The eccentric may be provided with a driving connection, as a link, to cause the desired short reciprocatory movement of the head. As a result 50 of the reciprocation the belt will be intermittently contacted with the rotating brush for cleansing purposes.

The belt may also be caused to pass over a 55 pulley, which pulley is preferably provided with an eccentric adjusting arrangement to tighten the belt, and with a concentric ratchet and pawl arrangement to cause the gradual replacement movement of the belt as a result of the reciprocation above described.

70 In the drawings, which show one embodiment of the invention:—

Figure 1 is a side elevation of the arrangement with the abrasive carrier in contact with the wrapping strip;

75 Figure 2 is a rear view of the arrangement with

the abrasive carrier removed from the wrapping strip;

Figure 3 is a front view partly in section upon the line 3—3 of Figure 1;

Figure 4 is a transverse sectional view upon 80 the line 4—4 of Figure 3;

Figure 5 is a view of the wrapped package indicating the application of the surface-treated wrapping material; and

Figure 6 is a fragmentary sectional view upon 85 the line 6—6 of Fig. 2.

In Figures 1 to 4 the angle supports 10 extend upwardly from the wrapping machine and are bolted at 12 to the machine-frame 11 (see particularly Fig. 1) which may be part of a wrapping machine or some other mechanism for receiving and further processing the wrapping sheet after the surface treatment. The supports bars 14 have adjustable slotted connections 13 to the side members 10. At their opposite ends the bars 14 95 receive the rod 15, said rod being fixed in openings in the ends of the support bars 14 by the set screws 16.

The frame 17 of the surface treating mechanism is suspended from the rod 15 by the hangers 100 18, which are centered by the collars 19 (see particularly Fig. 2) said collars having a slotted adjustable connection at 20 to the frame 17. The lower portion of frame 17 is recessed at 30 and is provided with a rearwardly extending arm 31, 195 the rear end 32 of which is provided with a boss 33. Into an opening through the boss 33 is press fitted a pivot rod or stud 120 (see particularly Fig. 6).

The reciprocating head 45 is also provided with 110 a rearwardly extending arm 46 which is pivotally supported at its rear end upon the said rod 120 by the nipple or hub 121.

The hub or nipple 121 carries and forms a bearing for an eccentric belt tightening bushing or collar 122 which is provided with the knurled end portion 35. The collar 122 may be locked in any adjusted position by the wing screw 36, which screw has a threaded shank or extension 124, fitting into a tapped hole in the end of the stud 120. The wing screw 36 clamps the base 125 of the eccentric 122 against the end 126 of the stud 120.

To turn the ratchet wheel 38 the arm 46 is provided with an upwardly-projecting ear 46' 125 carrying an actuating pawl 47, the detent pawl 48 being secured to the arm 31.

The belt 50 which may carry an abrasive such as emery or another surface-treating material, 130 passes over the head 45 and the knurled pulley 37. The head 45 is attached to a yoke 51, said yoke being pivotally connected to the eccentric head 52 by the line 53. The eccentric head 52 is carried by the shaft 52' which also carries the rotary brush 54 and the V-pulley 55. The V-pulley 55 135 is driven through the round belt 56 from the small V-pulley 57 and the electric motor 58.

The head 45 is moved into and out of contact with the material to be treated by the channel-shaped rack 65, which actuates a push rod 66 having a pivotal connection at 67 to the forward end of the arm 31 of the frame 17. The push rod 66 slides through the head 68 of the swivel stud 68' and is provided with the adjustable collars 69 and 70, the spring 71 between the collar 69 and the head 68 of the stud 68' serving as a resilient transmission between the rack 65 and the rod 66. The stud 68' is carried by a hanger 72 which has a slotted connection 73 to the rack 65. The rack 65 is guided upon the pulley 74 and is 145 150

reciprocated through the arm 75 from the shaft 76, the said arm being rigidly connected to said shaft by the split collar 77.

The backing plate 85, over which the sheet 104 is passed, has a soft and compressible facing 86, and it is provided with a hanger 87, which is supported upon the horizontal rod 88. The ends of the rod 88 are provided with hangers 89 which are adjustably fixed upon the rods 90 by means of the set screws 91. The rods 90 are carried upon the vertical support rods 92 by the clamps 93.

The sheet roll 100 is supported upon the rod 102, the ends of which rest in the recess 103 in the frame 11. The wrapping sheet 104 is passed over the guide rollers 105, 106, 107, 108, the rollers 107 and 108 serving to correctly position it when it passes between the head 45 and the backing plate 85. The feed rolls 109 and 110 which may respectively have facings of rubber 20 and steel, are supported on the frame 11 and with the shaft 76 are driven from the main machine.

In operation the wrapping mechanism will cause the feed rolls 109 and 110 to advance the wrapping sheet 104 intermittently. Between successive advances of sheet 104, the mechanism will also actuate the shaft 76 to elevate the rack 65 resulting in a pressure contact between the abrasive face of the carrier belt 50 and the surface 30 of the sheet 104, the sheet being pressed by the head 45 against the felt facing 86. The amount of pressure may be regulated so that the surface will be removed only to the desired extent, by the collar 69, which controls the compression of 35 the spring 71, said spring serving as a transmission member. During all this time the head 45 and the contact face of the belt 50 are being rapidly reciprocated by the eccentric head 52 through the link 53, said head 52 being driven 40 from the motor 58 through the V-pulleys 55 and 57 and the belt 56.

Immediately upon the next advancing movement of the rolls 109 and 110, the rack 65 with its arm 75 will be moved downwardly by the shafts 45 76 into the position shown in dotted lines. As a result that the push rod 66 will withdraw the head 45 from contact with the surface of the wrapping sheet.

The reciprocation of the head 45 as above described will result in oscillatory movement of the arm 46 with the attached pawl 47, turning the ratchet 38, as a result the knurled pulley 37 will be rotated and the belt 50 will be advanced, the 50 detent pawl 48 preventing retrograde movement 55 of the ratchet. The pulley 37 will turn with the ratchet 38 and its knurled face will prevent slippage between the belt and the pulley. The slack in the belt 50 may be taken up by adjusting the eccentric bushing 122 by gripping its knurled head 35, after loosening the wing screw 36, which bushing 122 after adjustment may be locked in position by the wing-screw 36.

The above-described reciprocation of the carrying head 45 will also cause an intermittent contact of the rotating brush 54 with the abrasive surface of the belt 50, as a result removing dust and other abraded particles therefrom. As shown in Figure 1 the belt is moved rearwardly 65 on top and advanced forwardly on the bottom, so that the brush 54 is contacted with the belt shortly after it is removed from the head 45.

The brush 54 may be replaced under suitable conditions by other cleansing devices, or even by 70 devices which are adapted to place surface treat-

ing materials or substances upon the carrying belt.

It will be noted that the frame 17 is pivotally suspended while the contact head 45 and its arm 46 are in part supported from the frame 17 by pivotal connection with the rod 120 and are in part suspended by the link 53.

Since the wrapping sheet or web 104, particularly when of the type of material known as "Cellophane" is formed in such a fashion that the grain of the base will extend longitudinally thereof, the abrasion or scratching will similarly extend longitudinally along the grain and will therefore weaken the sheet or web as little as possible.

The width of the belt carrier 50 and the amount of the reciprocatory movement from the eccentric 52 may be conveniently controlled so that only as small a space upon the sheet or web as is necessary will be treated or abraded. In one installation the belt has a width of 1", the eccentric causing the head to move through an amplitude of 1". As a result an abraded surface of 1" x 1" was formed.

It will be noted that the rolls 109 and 110 and the shaft 76 may be so timed and correlated with the wrapping machinery that the abrasion of the sheet or web will only take place when it is not being advanced.

Upon Figure 5 is shown a typical cigarette package 120 wrapped in a transparent material, the wrapping having an abraded portion 121, the dotted lines 122 indicating the size of the sheet before it is attached to the cigarette package. It will be noted that only a relatively small portion of the wrapper is affected, so that there is but an inconsequential loss in transparency and moisture-proof qualities. Moreover since the abrasion was along the grain, the wrapper is weakened to but a slight extent. The depth of the abrasion and/or the amount of the removal of the surface material may be conveniently regulated by the adjusting collar 69 and the spring 71 and may be varied with the particular wrapping material and with the particular surfacing employed.

It is obvious of course that the mechanism and process of the present invention under suitable modification may be applied to surface treating operations other than those involving abrasion and that the mechanism may conveniently be associated with machinery other than wrapping or cigarette packaging machinery of the character described. By suitable changes the abrasion treatment might be directly applied to the wrapped package or preparations.

The various elements of the mechanism shown may be constructed of any suitable materials, and it has been found satisfactory in one instance to form the bars 14, the wing screw 36, the pulley 37, the ratchet 38, pawls 47 and 48, yoke 51, the eccentric 52, the hub 53, the swivel head 67, the clamps 93 and the stud or pivot rod 120 of steel; the frame hanger 18, the collars 19 and the eccentric 35 of bronze; and the frame 17, the arms 31 and 46, the head 45, the rack 65 and the backing plate 85 of aluminum; the head 45 and the arm 46, with its hub 121, and the frame 17 and the arm 31, and the pulley 37 and the ratchet 38 respectively preferably consisting of unitary metal elements. The motor 58 may be of any convenient rating, a 1/30 H. P. motor turning at 1750 R. P. M. having been found satisfactory in one installation.

Where the wrapping material is to be wrapped

about cigarette packages of the approximate dimensions $2\frac{7}{8}'' \times \frac{7}{8}'' \times 2\frac{1}{8}''$, the wrapping strip may have a width of about $3\frac{3}{8}''$ and the abrasion mechanism a total height of about $6''$ from the swivel bar stud 68 to the top of the support 14 and a width of about $5''$ between the supports 14. These dimensions of course will vary greatly depending upon the width and character of the wrapping sheet, the construction of the wrapping machine, the type of surface treatment set forth.

As many changes and modifications could be made in the machine and method above described without departing from the essence of the invention, it is intended to include all such modifications, variations, and/or alternatives as will come within the scope of the appended claims.

What is claimed is:—

1. A surface treating mechanism comprising means to intermittently feed the material to be treated, a treating face to be applied to said material, means actuated from said feeding means to apply said treating face to said material during the intervals between said intermittent feeds, means to replace said treating face between applications thereof, and means to renew the treating face.

2. A treating apparatus comprising a series of feeding rolls to advance the material to be treated intermittently, a head adapted to be contacted with said material, a treating belt passing over said head, means to reciprocate said head into and out of contact with said material, and means to advance said treating belt.

3. A surface treating apparatus comprising a series of feeding rolls to advance a sheet of material to be treated intermittently, a head to be contacted with said material, and a backing plate opposed to said head, and means to grip said sheet between said head and said backing face, between periods of intermittent advance thereof, said head being provided with an abrasive facing and said backing plate being provided with a soft compressible facing.

4. A surface treating apparatus comprising a mechanism for advancing a sheet of material, opposed fixed and reciprocating heads between which said material is advanced, means to move said reciprocating head to press said material against said fixed head while the material is not being advanced, and to withdraw said head while the material is being advanced, and means to reciprocate said head during contact with said material, said reciprocating head being provided with the abrasive facing.

5. In an abrasive device, a carrier for the material to be abraded, means to advance said material over said carrier, an abrasive head, means to reciprocate said head into and out of contact with the material to be treated, and another means to reciprocate said head during contact with the material to be treated.

6. In an abrasive mechanism of the class described, a carrier arrangement for holding the material to be abraded, means to advance intermittently said material past said carrier, an abrasive face to be applied to said material upon said carrier, resilient means to apply said abrasive face to said material, and means to reciprocate said abrasion face during contact with said material.

7. In an abrading arrangement for transparent sheet materials, feeding rolls for advancing the material, a supply roll from which the material is unrolled, a fixed contacting plate with a felt facing, a plurality of intermediate rolls for caus-

ing the sheet material to pass over said fixed face, an abrasive carrying belt, a pulley and a head rigidly connected to each other supporting said belt, an eccentric associated with said pulley to tighten said belt, a ratchet associated with said pulley for advancing said belt, detent and actuating pawls for advancing said pulley, and means for causing said head to press said sheet against said felt facing.

8. In an abrading machine for transparent materials, a plurality of guide rolls over which the material is passed, a contacting head, a reciprocating drive, a resilient connection between said reciprocating drive and said head, and an abrasive carrying belt passing over said head.

9. In a wrapping tissue abrading machine, a carrying arrangement, means for advancing said tissue through said carrying arrangement, a contacting head, an eccentric arrangement for rapidly reciprocating said contacting head, a resilient driving connection for moving the contacting head into and out of contact with said tissue, and an abrasive carrying belt passing over said head.

10. In an abrasion arrangement, a carrier for the material to be abraded, an abrasion face, means for causing contact of said abrasion face with said material, means for cleansing the abrasion face, and means for causing alternate contact between the abrasion face and the material to be abraded, and the abrasion face and the cleansing means.

11. A process of treating sheets of material having a grained base and a non-cohesive surfacing to enable adhesive attachment thereto, which comprises pressing an abrasive against the surface of said sheet and rapidly reciprocating said abrasive longitudinally of the grain of said sheet while so pressed.

12. A process of treated coated moisture-proof sheet materials of cellulose derivatives having grained bases to enable the adhesive attachment of labels and stamps thereto, which comprises resiliently pressing an abrasive face against the surface and causing such face to reciprocate backwardly and forwardly along the grain thereof.

13. In a surface-treating mechanism, a web carrying device, a web receiving device, means for advancing said web from said carrying device to said receiving device past an intermediate place of treatment, a support over which the web is advanced at said place of treatment, surface-treating means movable toward and away from the face of the web opposite the support for abrading the exposed face thereof, and means for intermittently withdrawing the surface-treating means in timed relation with the movement of the web.

14. In a surface-treating mechanism, a web carrying device, a web receiving device, means for intermittently advancing the web from said carrying device to said receiving device across a place of treatment, a support over which the web is advanced at said place of treatment, a surface-treating tool at said place of treatment, means to move said surface-treating tool toward and away from the face of the web, and means to activate said last-mentioned means in timed relation with the intermittent movement of the web.

15. In an abrading mechanism for a continuous strip of sheet material, a roller feeding said sheet material, means to intermittently draw said sheet material from said roller across an intermediate place of treatment, a support over which said sheet of material is moved at said place of treatment, an abrading device at said place of treatment, means to move said abrading device inter-

mittently toward and away from the sheet of material upon said support for abrading the face thereof, means for renewing the abrading device, and means for actuating said last two mentioned 5 means in timed relationship with the movement of the sheet.

16. In an abrading mechanism to produce a longitudinal series of spaced abraded areas upon a continuous strip or sheet of material, a storage 10 roll, means intermittently to advance said sheet of material from said roll, an abrading device to be applied to the face of said sheet of material upon withdrawal from said roll to abrade the same, and means for withdrawing the abrading 15 device from the sheet of material in timed relationship with the movement of the sheet.

17. In an abrading mechanism to produce a longitudinal series of spaced abraded areas upon a continuous strip or sheet of material, a storage roll, means for causing an intermittent feed of 80 said sheet of material away from said roller, an abrading device to be intermittently applied to said withdrawn sheet of material to cause the formation of abraded areas, and means to co-ordinate the application of the abrading device to the movement of the sheet, so that the abrading device will be in abrading contact with the sheet when it is stationary and withdrawn from the sheet when it is moving.
